ROUND GAME

Erika Donath, Meissen, Germany

Application April 29, 1933, Serial No. 668,491
In Germany December 31, 1932

6 Claims. (Cl. 273—1)

This invention relates to a new game which is entertaining and at the same time instructive, and intended chiefly for children. The rules and manner of playing the game are exactly similar to the game of hide-and-seek played by children in the open, the several hiding places being distributed over a board which as picture represents a farm yard, a forester's lodge, a market place or the like. The game, besides being interesting, teaches the child for example all the buildings and other arrangements in a farm yard by choosing the different hiding places.

The characteristic feature of the invention is the employment of a cardboard box, in the lower part of which an intermediate plate is rigidly or exchangeably inserted at a certain distance from the bottom plate and over this intermediate plate a cover plate bearing the picture is arranged. Series of apertures, registering with one another are arranged, i. e. in the bottom small holes, in the intermediate partition and cover sheet larger holes, the latter being covered by an accurately fitting cap provided with a handle. The lid has on its short end walls flaps having extensions bent at right angle, which flaps engage in slots in the end walls and serve as supports for the lower part of the box inserted in the lid so that the bottom of the lower box part is situated at a certain distance from the bottom of the lid. The flaps are provided with tabs and are constantly pulled against the end walls by elastic bands or the like, so that the extensions always project into the interior of the lid.

In this position figures provided with a foot pin can be inserted in the shafts formed by the registering holes so that the pins engage through the holes in the bottom of the lower portion and extend into the free intermediate space, whereas the heads of the figures are situated under the cover plate so that the lid can be placed on the box and hides the figures. By pulling the two flaps by their tabs, the supporting extensions are moved outwards, release the bottom part which descends by gravity, comes into contact with the pins of the figures on the bottom of the lid, thereby causing the figures to lift their closing cap and to project a certain distance through the cover plate provided with the picture.

An embodiment of the invention is illustrated by way of example in the accompanying drawing in which:—

Fig. 1 shows the game in top plan view.

Fig. 2 is a part longitudinal section on a larger scale showing the box partly in the lid and supported on the flap extensions.

Fig. 3 is a similar view to Fig. 2 showing the box completely in the lid.

Fig. 4 shows on a larger scale a small portion of Fig. 1.

1 designates the lower part of the box with bottom 2, intermediate partition 3 and cover plate 4 provided with a picture. Registering holes are provided in the bottom, the intermediate partition and the cover plate. The holes in the cover plate are designated by 7 and can be each closed by a cap 6 provided with a handle 5, whereas the holes in the intermediate partition 3 are designated by 8 and those in the bottom by 9. The holes 7 and 8 are of the same size whereas the hole 9 is smaller than the holes 7 and 8. 60 The holes 7 in the cover plate 4 are off-set and provided with noses 4a. The caps 6 are correspondingly off-set and provided with recesses 6a fitting the noses 4a. The lid is removed from the box and placed upside down with its plate 10 lying flat on the table top. The part 1 of the box is then placed in the lid and is supported therein on bracket-like extensions 11, which are formed on flaps 12 hingedly connected by bands 13 to the end walls of the lid, and extend into the interior of the lid through slots 13. The flaps 12 are drawn continually against the end walls of the lid by elastic bands 14. The extensions 11 can be pulled out of the slots by pulling tabs 15 projecting from the lower ends of the flaps 12. 70 75 80 85

Fig. 1 shows the game in position for use. The game is played in the following manner: The players each receive a differently colored figure 17 made of wood, celluloid, composition or the like and provided with a foot pin 16. Each player also receives a mark or badge of a color corresponding to that of this figure. As when playing hide-and-seek in the open, one of the players turns away from the game and counts up to a predetermined number. During this time the other players hide their figures in the shafts formed by the holes and cover the holes with the corresponding caps. The figures now are hidden in the box. Each figure 17 is supported in one of the holes 8, its foot pin 16 extending through the corresponding hole 9 and resting on the plate 10 of the lid. The seeker then lifts one cap after the other until he finds one of the concealed figures, the number of caps lifted from empty shafts being noted as faults and the person to whom the found figure belongs then becomes the seeker. The game may be made particularly interesting by the seeker indicating a few points at which the persons whose figures hidden and 90 95 100 105 110

found at these points receive higher penalty marks.

When a figure has been found, the game is finished and it is very amusing when, as the part 1 5 descends, all the figures push open their caps and become visible, this being effected by pulling the two tabs 15. The figures are removed from the shafts which are then again closed by their caps and the part 1 is raised so that the game can 10 commence afresh.

I claim:—

1. A round game resembling the game of hide-and-seek played in the open, comprising in combination a box having a bottom with holes distributed over its surface, shafts formed in said box registering with said holes in said bottom, figures adapted to be inserted in any one of said shafts, pins one projecting from the lower end of each of said figures and adapted to extend 20 through the hole in said bottom place registering with the shaft in which the figure is inserted, caps each adapted to close one of said shafts and to conceal the figure inserted therein, a lid adapted in inverted position to accommodate said 25 box, elements in said lid adapted to support said box at a distance from the bottom of said inverted lid, and means for disengaging said elements to allow said box to descend in said lid by gravity and cause said figures to push open said caps 30 and project from said shafts.

2. A round game as specified in claim 1, comprising in combination with the box having a bottom with holes and the figures, an intermediate partition fixed in said box at a distance from 35 said bottom, and a cover plate in said box at a distance from said intermediate wall, said partition and said cover plate having holes registering with the holes in said bottom and forming with these holes the shafts for accommodating 40 said figures.

3. A round game as specified in claim 1, comprising in combination with the box having a perforated bottom, the caps, the figures and the 45 foot pins on said figures, an intermediate parti-

tion fixed in said box at a distance from said bottom, and a cover plate in said box at a distance from said partition, said partition and said cover plate having holes registering with the holes in said bottom and adapted to guide the inserted figures, the holes in said bottom adapted to guide said foot pins, and a handle on each of said caps adapted to facilitate their insertion and removal. 80

4. A round game as specified in claim 1, comprising in combination with the box and lid, said lid having slots on its end walls, extensions bent at right angles from said flaps projecting through the slots in said end walls and adapted to support said box at a distance from the bottom of said inverted lid. 85

5. A round game as specified in claim 1, comprising in combination with the box and lid, said lid having slots on its end walls, extensions bent at right angles from said flaps projecting through 90 the slots in said end walls and adapted to support said box at a distance from the bottom of said inverted lid, elastic bands connected to said lid and said flaps adapted to pull said flaps against said end walls, and tabs projecting from 95 said flaps adapted to allow said flaps to be pulled outwards to disengage said extensions from said box and allow said box to descend in said lid by gravity. 100

6. A round game as specified in claim 1, comprising in combination with the box having a bottom with holes, the caps and the figures, an intermediate partition fixed in said box at a distance from said bottom, and a cover plate in said box at a distance from said intermediate wall, 110 said partition and said cover plate having holes registering with the holes in said bottom and forming with these holes the shafts for accommodating said figures, the holes in said cover plate being set off and having each a nose, and 115 said caps being off-set corresponding to said holes and having each a recess fitting the nose of said holes. 120
